UNITED STATES PATENT OFFICE.

ERNEST G. CLARK, OF DE KALB, ILLINOIS, ASSIGNOR TO MELVILLE CLARK PIANO COMPANY, OF CHICAGO, ILLINOIS, A CORPORATION OF ILLINOIS.

NOTE-SHEET TERMINAL.

1,078,771.

Specification of Letters Patent. Patented Nov. 18, 1913.

Application filed May 18, 1911. Serial No. 628,078.

To all whom it may concern:

Be it known that I, ERNEST G. CLARK, a citizen of the United States, residing at De Kalb, in the county of Dekalb and State of Illinois, have invented new and useful Improvements in Note-Sheet Terminals, of which the following is a specification, reference being had to the accompanying drawings, forming a part thereof.

10 The purpose of this invention is to provide a convenient form of terminal lug for a perforated note sheet such as is used in automatic piano players, and the like.

It consists of the features and elements 15 described and shown in the drawings as indicated in the claims.

In the drawings:—Figure 1 shows the device applied to a note sheet and in use, for coupling the same to the feed roll of a 20 player action. Fig. 2 is a rear view of the device. Fig. 3 is a section taken as indicated at line 3—3, on Fig. 2.

As illustrated in the drawings, this device consists of a tab made from linen or 25 other suitably tough fabric and having the form of an isosceles triangle, 1, of which the two equal angles, 1^a, are blunted or rounded, and the odd angle or apex is extended to form the lug, 1^b; this lug is perforated and has secured in it an eyelet, 2, which also engages the lug, 3^b, of a smaller tab, 3, which is also made in the form of an isosceles triangle with its corners, 3^a, rounded, but positioned with its base, 3^c, below the base, 1^c, of the larger triangle and 35 parallel thereto.

The interior or proximate faces of the two tabs or leaves of the device are gummed, so that they may be readily applied to the 40 opposite surfaces of a note sheet, A; this adapts the device to serve as a terminal fitting for the note sheet for coupling it to the driving roll, B, of the player action, by engagement of the eyelet, 2, with the pin, 45 B¹, positioned thereon. The tab being constructed of fabric instead of paper, has more tenacity than the sheet itself and is better adapted to contain the eyelet or any device intended to engage the driving pin, 50 B¹. By virtue of its triangular form, it serves to distribute the tensile strain from the eyelet to an area of the paper great enough to withstand such strain. Since practically none of such tensile strain could 55 be transmitted to the paper lying directly

at either side of the tab, the corners of the note sheet are cut off along the lines, A¹, in the direction of the sloping sides of the tab, both improving the appearance of the sheet and decreasing the liability of its becoming torn at these loose corners.

As the sectional view of Fig. 3 indicates, the two triangular portions or leaves of the tab together with their respective lugs, are all formed from a single piece of fabric 65 folded along the line, 5; it is obviously immaterial, however, whether one piece or two be used in this construction, since both tabs are securely connected by the engagement of the eyelet with their respective lugs.

By virtue of the fact that the tab, 3, is smaller than the tab, 1, the total thickness of the note sheet varies gradually rather than abruptly, as it would along the line, 1^c, if the tabs were of equal size, and this 75 graduated thickness renders less likely any breaking of the paper along this line, such as would tend to occur in the constant rolling and rerolling of the sheet in use.

I claim:—

1. In combination with a perforated note sheet, a terminal tab therefor comprising two leaves of fabric having the form of isosceles triangles, each with a lug projecting from the apex angle of the triangle, and 85 an attaching device carried by said lugs, the mutually facing surfaces of the two leaves being secured to the opposite faces of the note sheet, and the note sheet having its edges near its terminal portion slanted in 90 line with the respective sides of the triangular tabs which include the aforesaid apex angle.

2. In combination with a perforated note sheet, a terminal tab therefor comprising two leaves of fabric having the form of isosceles triangles, each with a lug projecting from the apex angle of the triangle, and each having the other two corners of the triangle rounded off in smooth curves blending into the sides and base of the triangle, the mutually facing surfaces of the two leaves being secured to the opposite faces of the note sheet, said note sheet having its lateral edges near its terminal portion slanted in 105 line with the respective sides of the tabs which include the apex angle, and an attaching device carried by the lugs.

3. In combination with a perforated note sheet, a terminal tab therefor, comprising 110

two leaves of fabric having the form of isosceles triangles, each with a lug projecting from the apex angle of the triangle, and an attaching device carried by said lugs, 5 said note sheet having the lateral edges near its terminal portion slanted in line with the respective sides of the tabs which include the apex angle, and one of the leaves being of less area than the other and having that 10 portion of its margin which is directly opposite the lug lying within the margin of the other leaf, the mutually facing surfaces of the two leaves being secured to the opposite faces of the note sheet.

15 4. In combination with a perforated note sheet, a terminal tab therefor, comprising two leaves of fabric secured, respectively, to the opposite faces of the note sheet and each having a lug projecting longitudinally from 20 the end of the note sheet, and an eyelet in said lugs securing them together and adapted to serve for attaching the end of the note

sheet to the driving roll of a player mechanism.

5. A device for the purpose indicated, 25 comprising two leaves of fabric having each a lug projecting from one side, an eyelet in the lugs securing the leaves together, one of the leaves being of less area than the other and having that portion of its margin which 30 is directly opposite the lug lying within the margin of the other leaf, and the mutually facing surfaces of the two leaves being gummed for securing them respectively to opposite sides of a sheet which may be inter- 35 posed between them.

In testimony whereof I have hereunto set my hand at De Kalb, Ill., this 16th day of May, 1911.

ERNEST G. CLARK.
